UNITED STATES PATENT OFFICE.

GEORGE O. LEOPOLD, OF PHILADELPHIA, PENNSYLVANIA, ASSIGNOR TO NORTH BRO'S M'F'G CO., OF PHILADELPHIA, PENNSYLVANIA, A CORPORATION OF PENNSYLVANIA.

DESIGN FOR A SCREW-DRIVER.

44,573.

Specification for Design.

Patented Aug. 26, 1913.

Application filed October 7, 1911. Serial No. 653,415. Term of patent 14 years.

To all whom it may concern:

Be it known that I, GEORGE O. LEOPOLD, a citizen of the United States, residing in Philadelphia, Pennsylvania, have invented a certain new, original, and ornamental Design for a Screw-Driver, of which the following is a specification, reference being had to the accompanying drawing, forming part thereof.

The figure is a side view of a screw driver showing my design.

I claim:—

The ornamental design for a screw driver, as shown.

GEORGE O. LEOPOLD.

Witnesses:

Wm. E. SHUPE,
Wm. A. BARR.
